UNITED STATES PATENT OFFICE.

FRANK L. PUTNEY, OF SUNSHINE, WYOMING.

STIRRUP.

932,574.

Specification of Letters Patent. Patented Aug. 31, 1909.

Application filed April 16, 1908. Serial No. 427,373.

To all whom it may concern:

Be it known that I, FRANK L. PUTNEY, a citizen of the United States, residing at Sunshine, in the county of Big Horn and State 5 of Wyoming, have invented certain new and useful Improvements in Stirrups, of which the following is a specification.

This invention relates to harness, and more particularly to stirrups, and has for its object to provide a stirrup arranged to release 10 the foot of the rider therefrom when caught in the stirrup.

Another object is to provide a stirrup of a serviceable type the releasing means of 15 which will be effective in operation, and not liable to derangement.

Another object is to provide a stirrup of 20 this class which may be attached to the saddle in the usual manner, and which may be easily manufactured.

Other objects and advantages will be apparent from the following description, and it will be understood that changes in the specific structure shown and described may 25 be made within the scope of the claims without departing from the spirit of the invention.

In the drawings forming a portion of this specification and in which like numerals of 30 reference indicate similar parts in the several views, Figure 1 is a plan view of the rear of the stirrup, Fig. 2 is a side view of the stirrup in engaged position, Fig. 3 is a detail view of the pivot and adjacent operating portions, Fig. 4 is a similar view at right angles to Fig. 3, Fig. 5 is a top view of the stirrup, Fig. 6 is a side view of the stirrup in disengaged position, and Fig. 7 is a sectional view at right angles to Fig. 6 35 showing the stirrup in disengaged position. Fig. 8 is a detail front view of the foot engaging means showing a detachable extension engaged thereon.

Referring now more particularly to the 40 drawings, there is shown a stirrup having a top portion 10 and a bottom portion 11 pivoted thereto. The top portion 10 comprises downwardly extending spaced arms 12 connected by an arched portion 13. The arch 45 13 supports posts 14 carrying therebetween spaced bars 15 and 16 arranged for the reception of a wide and a narrow stirrup strap respectively. The posts extend upwardly 50 beyond the bars and carry therebetween a bar 18 offset forwardly to allow the passage 55 of the stirrup strap thereunder to the

bars below, the forward pressure of such strap upon the bar 18 serving to hold the base of the stirrup against forward movement. The lower end portions of the arms 60 12 are recessed longitudinally on their inner sides as shown at 20. A releasing member 22 comprising a foot-engaging bar 24 carrying spaced downwardly extending arms 23 disposed outwardly of the arms 12 is secured 65 pivotally to the top portion 10 by means of pins 24' engaged through the arms 23.

The foot engaging bar 24 is offset forwardly of the stirrup and is connected with 70 the arms 23 by angular connecting arms 25 extending rearwardly between the arms 14 and outwardly therebehind to join the arms 23. Spaced rods 27 are carried by the foot engaging bar 24 at its junction with the 75 arms 25 and are engaged slidably in openings 26 formed in the arch 13. Helical springs 28 are engaged around the rods 27 and bear against the foot engaging bar 24 and arch 13 to hold the bar at the forward 80 limit of its movement. The extremities of the arms 23 are provided with hooks 29 having rearwardly extending bills for a purpose to be subsequently indicated.

The bottom portion 11 comprises a foot 85 receiving bar 30 carrying upwardly extending fingers 31 at its opposite sides, the fingers being disposed inwardly of and against the arms 12 for sliding movement within the recess 20. Recesses 51 are formed in the 90 outer sides of these fingers adjacent to their bases, having beveled sides and opening on the forward edges of the fingers. Upwardly and outwardly extending hook members 32 are carried by the bottom portion 11 near 95 the base of and outwardly of the fingers 31, and extending upwardly in spaced relation therewith, being located at the rear side of the stirrup. The hooks 32 are engaged over the bills of the hooks 29, as shown. 100

The lower ends of the arms 12 are engaged in the space between the fingers 31 and the hooks 32, and seated against a cushion of resilient material 35 located at the bottom of the space between the hooks 32 105 and the fingers 31, excessive play between the two parts being thus prevented. Projections 50 are formed on the inner sides of the arms 12, near their lower ends and near their forward edges, being slidably engaged 110 in the recesses 51 in the fingers 31. Passages 21 are formed through these arms adjacent

the upper ends of the fingers, their inner ends being reduced in size, as shown. Recesses 37 are formed in the outer side of the fingers 31 near their upper ends, and register with the inner ends of passages 21 formed through the arm 12. Headed pins 38 are engaged slidably in the openings 21 with the heads extending outwardly of the stirrup and their opposite ends engaged 10 snugly in the recesses 37 of the fingers 31. Helical springs 39 are engaged slidably around the pins 38, bearing outwardly against their heads and tending to force the pins 38 out of engagement with the recesses 37 of the fingers 31. This movement of the pins 38 is normally stopped by the arms 23 which are then located over the outer end of the opening 20.

It will be seen that should a rider fall 20 from the saddle and his foot become entangled in the stirrup, his foot will strike against the foot engaging bar 24 thus operating the arms 23 upon their pivots. Movement of the arms 23 consequent upon 25 this engagement will remove obstruction from the outward movement of the pins 38 which will be forced outwardly, releasing the fingers 31 and the pressure of the ankle of the rider forwardly upon the foot receiving portion 30 will allow twisting motion of 30 the base part 11, which will result in the base portion dropping away from the upper portion 10. This disengagement is further facilitated by reason of the fact that the 35 hooks 29 will be partly inverted as a result of the operation of the arms 26.

In Fig. 5 there is shown a bar 52 secured to the forward edge of the foot engaging bar 24 by means of screws or other suitable 40 means. The bar 52 extends laterally of the bar 24 to offer a wider foot engaging surface to insure positive operation of the device.

What is claimed is:

45 1. An article of the class described comprising a hanger arranged for engagement with a stirrup strap and having spaced pendent portions, a foot piece having spaced upwardly extending portions slidably engaged 50 between the pendent portions of the hanger and having projections thereon, said pendent portions having intermediate pivot passages therethrough, said upwardly extending portions having recesses registering with 55 the passages, pivot pins disposed slidably in the passages and projecting into the recesses, resilient means engaged with the pins under tension to force them out of engagement with the recesses, and a release member comprising a forwardly extending portion and 60 spaced intermediately pivoted arms having rearwardly extending hooks engaged beneath

the projections of the foot piece, said arms being disposed slidably over said passages opposite the recesses, said release member 65 being adapted to release said pins and projections when said forwardly extending portion is pressed rearwardly.

2. An article of the class described comprising a top member, a bottom member detachably locked thereto, said top member comprising an arch portion carrying spaced arms depending therefrom, said arch portion carrying also integral spaced posts having a plurality of bars extending therebetween, said top member having a releasing member pivoted thereto comprising a foot engaging bar extending laterally of the stirrup and forwardly thereof for engagement against the foot of a rider when presented 80 upwardly and forwardly through the stirrup, said releasing member comprising also spaced arms disposed outwardly of and pivoted to said arms of the top member and having hooks at their ends having rearwardly extending bills, said bottom member comprising a foot bar having spaced upwardly extending fingers at its opposite ends, said fingers being disposed inwardly of and detachably pivoted to said first named 90 arms carried by the top member, said fingers being arranged to be detached from engagement with the top portion upon operation of said releasing mechanism, said bottom member having also upwardly extending hooks 95 outwardly of said fingers said last named hooks having forwardly extending bills adapted for interlocking engagement with said first named hooks carried by the releasing member, and means for holding said releasing member yieldably against operation. 100

3. In a stirrup of the class described, the combination with an upper portion, and a pivoted release member, carried thereby and having a hook portion at its lower end, of a 105 foot bar member carried pivotally by the upper portion and having a laterally extending projection engaged over said hook, said releasing member having forwardly extending portions adapted to be engaged by the foot 110 of a rider when presented upwardly through the stirrup for pivotal operation thereof to disengage the hook from said projection, and a pivot member engaged through the upper portion and with the foot bar, beneath said 115 releasing member and adapted to be disengaged from said foot bar member upon operation of said releasing member.

In testimony whereof I affix my signature, in presence of two witnesses.

FRANK L. PUTNEY.
